UNITED STATES PATENT OFFICE.

BENJAMIN B. MORGAN, OF ANN ARBOR, ASSIGNOR OF THREE-FOURTHS TO
HENRY P. GLOVER, ENOCH C. BOWLING, AND EDWARD R. E. COWELL,
ALL OF YPSILANTI, MICHIGAN.

RAILWAY-CROSSING.

SPECIFICATION forming part of Letters Patent No. 403,060, dated May 7, 1889.

Application filed October 23, 1888. Serial No. 288,916. (No model.)

To all whom it may concern:

Be it known that I, BENJAMIN B. MORGAN, of Ann Arbor, in the county of Washtenaw and State of Michigan, have invented a new and useful Improvement in Railway-Crossings, of which the following is a specification.

My invention consists in an improvement in railway-crossings, hereinafter fully described and claimed.

10 The figures are both plan views.

H H and I I represent the rails of two intersecting railway-tracks, the rails of each track being broken at their intersections.

B represents a sliding plate set in a suitable bed-plate and long enough to reach diagonally across the crossing, and carrying thereon two rail-sections, F F, adapted to complete the rails I, and two rail-sections, G G, adapted to complete the rails H H.

15 C and D represent two similar but shorter plates, one of which is located at each of the other intersections of the rails H I, and each of these shorter plates carries two rail-sections, F and G, adapted to complete the rails I and H, respectively.

The long plate B and the two shorter plates, C and D, may be connected together, so as to be moved simultaneously from a single point in a number of ways, some being illustrated

20 in the drawings, or they may be moved separately, as shall be found more convenient.

In Figure 1 the central plate, B, is connected by a pitman, L, with one arm of the bell-crank lever A, which is moved by any ordinary switch mechanism, and the plates D and 35 C are connected by pitmen L with similar bell-crank levers, A' and A², the other arms of which levers are connected by pitmen M M with the other arm of bell-crank lever A, so that when lever A is moved its motion is communicated to levers A' and A², and the plates B, C, and D are moved simultaneously; or the three pitmen L may be connected by a cross-bar, E, (shown in dotted lines in Fig. 1,) whereby the levers A' and A² may be dispensed 40 with and the plates B, C, and D all moved directly from the lever A. As shown in Fig. 2, the plates C and D are connected directly with the plate B by the cross-bar E.

45 What I claim as my invention, and desire to secure by Letters Patent, is—

In a railway-crossing, the combination of the tracks H and I, broken at their intersections, with the movable plate B, carrying the four rail-sections F F and G G, and the movable plates C D, each carrying two rail-sections, F G, substantially as shown and described.

BENJAMIN B. MORGAN.
